[57] CLAIM

The ornamental design for a inkjet printer, substantially, as shown and described.

DESCRIPTION

FIG. 1 is a perspective view of an inkjet printer in accordance with the present invention;
FIG. 2 is a top plan view thereof;
FIG. 3 is a front elevational view thereof;
FIG. 4 is a left side elevational view thereof;
FIG. 5 is a rear elevational view thereof;
FIG. 6 is a right side elevational view thereof; and,
FIG. 7 is a bottom plan view thereof.

The broken line showing of potential electrical interconnect plugs in FIG. 4 and in FIG. 6, and of potential pushbutton keys in FIGS. 1-4, is for illustrative purposes only and forms no part of the claimed design.
